RULING MACHINE

John Davies Moore, Montreal, Quebec, Canada

Application February 23, 1952, Serial No. 273,048

9 Claims. (Cl. 33—32)

1

The present invention relates to paper ruling machines.

Paper ruling machines in general consist of a frame or bed over which the sheet to be ruled is transported by means of an endless belt beneath transverse beams holding multiple arrangements of pens that are set to give the desired spacing of the lines to be ruled.

Generally the length of the lines relative to the length of the sheet to be ruled is controlled by the raising or lowering of the pen supporting beams. The raising or lowering of the pen supporting beams is controlled and actuated in sequence through a system of cams which in turn are actuated by the paper conveying mechanism.

While many of the ruling machines at present available are capable of producing ruled stock at high speeds there is one common disadvantage in this prior art apparatus in that the accuracy and alignment of the beginning or termination of a ruled line is dependent to a great deal on the care and precision with which the pens are set up in the pen beams and the correct setting of the beam lifting cams.

For example, if a sheet has to be ruled first in regular spaced apart longitudinal lines and then cross ruled in transverse lines across the ends of the longitudinal lines, it is necessary for all the longitudinal lines to start exactly in alignment so that there will be no lines extending when the transverse lines are ruled. If for example, the sheet has 30 spaced apart longitudinal lines, it means that 30 pens must meet the paper at exactly the same point, or when the pen beam is dropped, any of the pens which are aligned so as to protrude slightly beyond the others will produce a line before the remaining pens contact the paper.

A further disadvantage of most of the prior art apparatus is that the paper is maintained in contact with the conveyor carrying it beneath the pen beams by a plurality of endless cords which pass between the pens and are supported in their non-operative run above the machine by standards and rollers positioned at each end. To give adequate working space above the bed of the machine these standards have to project considerably above the machine. They also occupy considerable floor space, particularly if two machines are connected in dual or L to produce multiple transverse lines with a single run. Due to the complex setting up required for the present ruling machines, the use of two combined machines is the most practical manner to achieve production results.

The flexibility of the endless cords also allows the paper at times to be fed beneath the pens with a wave or buckle in it so that the raised portion of the paper contacts the pens before the remainder of the sheet.

The present invention recognizes these disad-

5

2

vantages and aims to provide a compact, efficient ruling machine that embodies means whereby the setting up time is considerably reduced and the accuracy and alignment of lines made positive.

Sheets to be ruled that require "blind" striking and mitering can also be made to perfection in the present apparatus.

Further, a ruling machine constructed in accordance with the invention eliminates the necessity for any overhead construction so that the whole top of the machine is clear and open to the operator.

Accordingly, the invention is a ruling machine having in combination with a supporting frame, at least one pen beam pivotally mounted on the frame, and a paper supporting carriage mounted on the frame for reciprocal movement beneath the pen beam. A template supporting frame is also mounted on the machine frame above the paper supporting carriage and is adapted to be moved beneath the pen beam when engaged by the paper supporting carriage. Means are provided on the paper carriage to pick up, carry beneath the pens, and eject individual sheets of paper when ruled.

A main feature in the present ruling machine resides in the use of a thin template which is mounted on the template supporting carriage and interposed between the paper carried by the paper supporting carriage at the beginning and/or ending of the desired lines to be ruled. The pen beams are mounted on the frame so as to be readily interchangeable and the ink supply means is also interchangeable and capable of preset-up. This means that the pens may be set up on the beams in any desired alignment and spacing and the ink supplying wicks inserted to suit any desired line and color arrangement outside of the machine while the machine is in use. In this manner various layouts can be prepared and run off in sequence with the minimum of machine stoppage.

Having thus generally described the nature of the invention, particular reference will be made to the accompanying drawings wherein a preferred construction of a ruling machine in accordance with the invention is illustrated, and in which:

Figure 1 is a plan view of a preferred construction of a ruling machine in accordance with the invention.

Figure 2 is a diagrammatic view of a portion of a sheet as it may be ruled by the present apparatus.

Figure 3 is a fragmentary view of a template used to produce the vertical line formation on the sample sheet shown in Figure 2.

Figure 4 is a plan view of a portion of the apparatus shown in Figure 1 to illustrate in more detail the arrangement of the sheet carrying frame and template.

Figure 5 is an enlarged sectional view of a portion of the apparatus shown in Figure 1 along the line 5—5 to illustrate in more detail the relative position of the upper and lower track and the lever mechanism actuating the paper release.

Figure 6 is a sectional view of Figure 1 along the line 6—6 to illustrate in side elevation the construction of the apparatus.

Figure 7 is a sectional view of Figure 1 along the line 7—7 to illustrate in more detail the pen raising cams of the paper holding carriage.

Figure 8 is a horizontal cross section of the construction shown in Figure 1 with the paper supporting carriage at a position approximately mid-way of the stroke of the machine to show more clearly the relative position of the carrier, the bed board, the actuating linkage and the frame.

Figure 9 is an enlarged detail view of a portion of the construction shown in Figure 6 to illustrate in more detail the relative position of template holder, paper carrier, bed board and paper release mechanism in the terminal position at the end of a stroke prior to picking up a new sheet of paper.

Figure 10 is a view corresponding in location to Figure 9 illustrating the initial forward movement of the bed board relative to the template supporting frame with the lower track raised.

Figure 11 shows the bed board and template supporting frame at the other terminal position at the end of the stroke with the paper sheet being carried off by the paper removing mechanism.

Figure 12 is a diagrammatic view in horizontal cross section of the portion of the apparatus shown in Figure 10 to illustrate in more detail the relative position of the paper engaging (gripper) and the actuating mechanism operating this member.

Figure 13 is a sectional view of the construction shown in Figure 1 along the line 13—13 to illustrate in more detail the removable pin holding the pen beam and also the lever raising the pens when actuated by the pen raising cams positioned on the frame.

Figure 14 is a diagrammatic view in cross section of the ink feeding arrangement of the apparatus illustrating the construction in more detail.

Figure 15 is a diagrammatic view in plan of the ink feeding arrangement showing the relative position of the main ink supply elements and the preferred method of feeding of the front and rear pens.

Figure 16 is an enlarged sectional view of a preferred form of ink reservoir along the line 16—16 of Figure 15.

Figure 17 is a diagrammatic view partially in section of the paper feeding, template supporting frame, bed board, and paper removing arrangement as it would appear in a terminal position at the end of a stroke as partially shown in enlarged detail in Figure 11.

Figure 18 is an enlarged fragmentary view of the front portion of the mobile bed board to illustrate in more detail the resiliently biased cam arrangement governing the operation of the paper holding gripper as it would appear at the end of the operating stroke.

Figure 19 is an enlarged diagrammatic view in plan of a portion of the construction shown in Figure 1 to illustrate in more detail the relative position of the cam carrying bar at the end

of the forward stroke with the bar locking cam in down position, retaining the bar in one terminal position with the pen beams raised.

Figure 20 is a view in side elevation of a portion of Figure 19 to show in more detail the construction and relative position of the bar locking cam and one of the pen beam holding cams.

Figure 21 is a fragmentary view in plan corresponding in location to Figure 19 with the cam carrying side bar in the other terminal position with the bar retaining cam raised and the pen beams actuating cams allowing the pen beams to move into operative position.

Figure 22 is an enlarged fragmentary view of a portion of the construction shown in Figure 21 in side elevation to illustrate the relative position and construction of the bar retaining cam and pen beams in the second terminal position.

Figure 23 is a sectional view of Figure 21 along the line 23—23 to illustrate the relative position of the bar locating cam, cam actuating plate supported by the template carrying frame and terminal position bar actuating pin attached to the template supporting frame.

With particular reference to Figures 1, 6 and 8 of the accompanying drawings wherein a paper ruling machine constructed in accordance with the invention is illustrated respectively in plan, transverse cross-section, and side elevation,

15 30 designates the main supporting frame of the machine on the upper portion of which there is mounted a fixed upper and a movable lower guiding track 12 and 14. The tracks 12 and 14 are positioned at each side of the frame and are 35 mounted on the inner surface of the top transverse frame members. The upper track 12 serves as a guiding means for a template supporting carriage 20, while the lower track 14 serves as a guiding means for a paper supporting carriage 22, the upper surface of which serves as a bed board.

40 A pair of pen supporting beams 24, 26 are 45 pivotally mounted between standards 30, 32, so as to extend transversely across the top of the frame 10 in spaced apart relationship and cam means are provided whereby the movement of the template supporting carriage 20 is adapted to raise and lower these pen supporting beams. This arrangement will be described in more detail later.

50 Figure 24 is a view in side elevation of the 55 machine showing the main supporting frame 10, the bed board 16, the template carrying frame 20, the paper supporting carriage 22, the pen supporting beams 24, 26, the standards 30, 32, the cam means 45, the endless cord conveyor 42, and the stacker or box 44. The machine is connected to one end of the machine so as to deliver the sheets of paper to a paper guide arrangement so that each sheet is aligned in the correct position for picking up by the paper supporting carriage 22. An endless cord conveyor means 42, is provided at the other end of the machine that is adapted in combination with an endless belt 280 to remove the ruled paper from the paper supporting carriage and deposit it in a stacker or box 44 mounted on the lower portion of the frame 10. This is merely shown by way of illustration and it will be understood that when the machine is utilized in the preferred tandem or L formation the paper would be delivered to a sheet turning device so as to position it to be transferred to the other machine of the L for subsequent ruling as is well known in the art.

55 The pen beams 24, 26 are adapted to support in spaced apart relationship any required number of ruling pens. Instead of the pens supported by the beams 24, 26 coming into direct contact with the paper at the beginning of a ruling stroke as is common in prior art machines, they are adapted to engage a template 21 mounted on the template supporting carriage 20. Each sheet

of paper is picked up and supported in flat condition during the ruling stroke by the paper supporting carriage 22 which is mounted on the track 14 for reciprocal movement beneath the pen beams. This reciprocal movement is imparted to the paper supporting carriage 22 by means of lever arms 50 which in turn are actuated by crank arms 52 driven from the crank wheels 54. The crank wheels 54 are mounted in suitable bearings 56 adjacent the lower portion 10 of the frame 10 and driven by means of a belt and pulley arrangement from a motor 60.

In order that the working of the machine may be more clearly understood the various portions will be described separately and in more detail. 15

Paper feeding device

The paper feeding belts 40 are adapted to feed the sheets of paper between a plurality of resilient holdown fingers 70 which are provided with rollers 72 to convey the paper forward on the belts. These paper holdown members 70 are adapted to act in co-operation with a curved base plate 73 mounted on the frame of the machine so that as the paper sheets are fed forward from the conveyor 40 they are individually moved upwardly between the top fingers 70 and the lower plate 73 until the forward edge encounters a plurality of spaced apart adjustable stop gauges 74. The stop gauges 74 are pivotally mounted by 30 means of a shaft 76 to the frame 10 and are actuated to raise at the required time to allow a sheet of paper to be picked up by the paper supporting carriage as will be described in more detail later. Lever means 80' are connected to each 35 end of the shaft 76 on which the stop gauges 74 are mounted. The lever means 80' is actuated by the paper supporting carriage 20 in one terminal position of the ruling stroke.

Paper supporting carriage

The paper supporting carriage 22 consists of a plurality of interconnected segments 27 which are supported and hingedly connected by means of plates 80 and intervening links 82. Each of 45 the segments 27 comprises a rectangular bar having a facing 28 on the upper surface so that when the carriage 22 is in ruling position the combined facings 28 serve as a bed board on which the paper is supported and held down during the ruling stroke. The plates 80 are secured to each of the segments 27 by means of an outstanding flange 87 so that each segment 27 is provided with an opposed parallel pair of downwardly extending plates 80, one at each end. 50

A pair of rollers 84 are mounted for rotation on each of the plates 80 by means of shafts 86 which extend outwardly from the plates 80 at each side of the carriage 22. The shafts 86 also serve as connecting pivots for the links 82. 55

When the paper supporting carriage 22 is travelling along the lower movable guide track 14 in a horizontal plane the links 82 keep the segments 27 in juxtaposed alignment but when the carriage 22 travels over the curved segments of the track 14, during the beginning and end of a ruling stroke, the links 82 allow the segments 27 to separate and follow the contour of the track. 60

The first 27a of the segments 27 is provided with a roller 90 that is inset in the segment 27a 70 for free rotation so as to facilitate the withdrawal of the paper sheet from the upper surface of the carriage 22 at the end of the ruling stroke. Pivotally mounted paper grippers 92 are provided on the leading edge of the forward carriage segment 75

27a so as to selectively grip and retain the leading edge of a sheet of paper fed between the paper holdown fingers 74. The paper grippers 92 are secured in spaced apart relationship to a common shaft 102 mounted for pivotal movement on and extending transversely across the front face of the carriage segment 27a.

The grippers 92 are resiliently maintained in "up" or "down" position by means of a cam 104 mounted on the end of the shaft 103 extending beyond the side of the segment 27a. A spring 106 acts against the face of the cam 104 so that as the grippers are moved into either position and the shaft 102 is rotated to move the cam 104 over centre in one direction or the other, the cam is resiliently retained in the selected position until the grippers 92 are again actuated through the movement of the paper supporting carriage. In Figure 18, the cam 104 is shown in "down" position, and in Figure 10, a gripper 92 is shown in "up," or closed position.

The movement of the grippers 92 between "up" and "down" position is controlled by means of an extension 93 provided on one of the grippers 92a positioned adjacent the outer edge of the segment 27a on the same side as the cam 104. This extension 93 is adapted to contact a fixed stop 108 extending from the frame 10 at the end of the ruling stroke so as to place the grippers 92 in the "up" position to release the paper. The grippers 92 remain in the "up" position throughout the return stroke and on the beginning of the ruling stroke the extension 93 contacts a resiliently biased stop 110 so as to urge the grippers 92 into the "down" or closed position to grip the paper between the stop gauges 74. The stop 110 is necessarily resiliently biased to allow the extension 93 to continue forward after the grippers 92 have been placed in "down" condition as well as allowing the extension 93 to pass the stop 110 during the return stroke.

Movable track

The lower track 14 is mounted on the frame 10 by means of slides 60 and co-operating slide blocks 61 secured to the upper portion of the frame 10 at each side. This arrangement allows for vertical up and down reciprocal movement of the track 14 relative to the track 12. This reciprocal movement is to provide clearance between the paper supporting carriage 22 and the template supporting carriage 20 at the end of each ruling stroke and during the return movement of the paper supporting carriage 22.

The reciprocal movement is imparted to the track 14 by means of a bellcrank 100 and lever 102 arrangement which is mounted on the upper portion of the frame 10 and is actuated through the sliding motion of a control bar 81 between two terminal positions on the frame 10.

With particular reference to Figure 5, an upper member 11 of the frame 10 is slotted as indicated at 120. The lever 102, which is fixedly mounted on a common shaft 103 with the bellcrank 100, extends through the slot to a pivoted connection with the control bar 81 by means of a pin 104 which extends at right angles from the end of the lever 102. This movement is transmitted to the other end of the frame by means of a connecting rod 121 extending between the bellcrank 100 and a second bellcrank 122 pivotally attached to the frame 10. A connecting shaft 124 extends from the bellcrank 100 transversely across the frame to a similar arrangement on the other side of the frame so that both sides of the track

14 are acted on simultaneously. The shaped arms 101 and 123 of the bellcranks 100, 122 are adapted to slidably engage with cam shaped extensions 63 provided on the slide blocks 61 so that pivotal movement of the bellcranks 100, 122 in one direction acts to raise the slides 61 and consequently the track 14 and in the opposite direction to lower the track 14.

The control bar

As previously mentioned, the control bar 81 is slidably mounted to one of the upper members of the frame 10. This is accomplished by providing elongated slots 130 in the bar 81 and having bolts 132 with outstanding heads inserted in the slots and threadably engaged with the upper flange of the track 12. The length of the slots 130 consequently limits the extent of travel of the control bar 81. However, a more positive stop is provided by a resiliently biased L-shaped stop 140, the lower leg 142 of which is adapted to fall into horizontal alignment with and to bear against the end of the bar 81 in one terminal position and remain in locked position until released by the movement of the template supporting carriage 20 at the end of the return stroke. The stopping of the control bar at the end of the forward, or ruling stroke, is resiliently damped by means of coil springs 143 supported on adjustable pins 144. The stop 140 is pivotally mounted on the upper surface of the track 12, see Figures 17 and 22, with a flat spring 146 bearing against the vertical leg 145 of the stop 140 so as to normally urge it forward and downward. A pin 141 extends at right angles from the top of the leg 145 so that it is normally disposed in the path of a vertical pin 161 extending from the side of the template supporting carriage 20. At the end of the return stroke of the carriage 20 the engagement of the pin 161 with the pin 141 tilts the stop 140 rearward, against the influence of the spring 146, so that the stop portion 142 is raised from engagement with the end of the control bar 81. The control bar 81 is then caused to travel to the terminal position under the influence of the coil springs 143 and more positively by the engagement of a stop pin 170 extending from the side of the template carriage 20 with a stop 172 protruding from the inner side of the control bar. See Figures 19 and 21.

Template supporting carriage

The template supporting carriage 20 consists of a rectangular frame 160 to the outer side members of which are journaled rollers 162 adapted to ride in the guide track 12. The frame 160 is shaped internally to accommodate the upper portions of the segments 21 of the paper supporting carriage 22 so that when both carriages are travelling together during the ruling action the carriage 22 is nested within the frame 160. The side members 163 of the frame 160 are provided with a series of equally spaced apart tapped holes 165 and template hold down strips 168 are mounted on the frame members 163 by screws 170 passing through the strips 168 and threadably engaged in these holes. In the construction illustrated, see Figures 3 and 4, the template 183 mounted on the template frame 160 is designed for the ruling of the vertical lines on the form shown in Figure 2. The template 21 is preferably made of a thin plastic material and is inserted between the frame members 163 and the hold down strips 168 at the front end and

sides of the frame 160 to accommodate the vertical ruling of the form illustrated.

Similar templates may be inserted at any position in the frame to control the beginning and ending of any lines. More than one template may be used simultaneously if so desired to suit the particular ruling of any form.

The side frame member 163A is wider and longer than the side frame member 163 and is provided with two stepped slots 190 which are adapted to accommodate outstanding cam plates which are adapted to engage and actuate the pen beams 24, 26, as will be described in more detail later.

Carriage actuating mechanism

The paper supporting carriage 22 and the template supporting carriage 20 are simultaneously moved forward and backward in the ruling and return motion along the guide tracks 12 and 14. This is accomplished by the connection of the lever arms 50 with a pair of fixed lever arms 53 secured to and extending downwardly from the template frame 160 of the carriage 20 at each side. The lever arms 53 each include an elongated slot 57 and pins 200 extending from each side 80b of the second segment 21b of the carriage 22, engage in the slots 57 so that the carriages 20, 22 are pivotally and slidably interconnected.

The upper ends of the lever arms 50 are pivotally connected at each side of the frame to the lower ends of the fixed lever arms 53. The lower end of each of the lever arms 50 is pivotally and slidably connected to brackets 206 extending from the frame 10 at each side by means of elongated slots 208 in the lever arms and headed pins or rivets 210. This arrangement allows the lever arms 50 under the influence of the crank arms 52 to move in a radial arc with the slots 57, 208 in the lever arms 53 and 50 compensating for the difference in effective length when the carriages 20, 22 move in ruling and return travel.

As previously briefly described, the crank arms 52 are pivotally connected between the lever arms 50 and the crankwheels 54. The crankwheels 54 are mounted in spaced apart relationship on a common shaft 59 journalled in the bearing blocks 56 adjacent the lower portion of the frame 10. The drive to the crankwheels 54 from the motor 60 is accomplished by a pulley 240 on the shaft 59 driven by a belt 242 from a pulley 244 secured to a shaft 246 journalled between the sides of the frame 10. A second pulley 248 is mounted on the shaft 246 and is driven from the motor 60 by a belt 250.

Paper discharge apparatus

The endless cord conveyor 42 at the discharge end of the apparatus serves to remove the ruled sheets of paper from the carriage 22 in co-operation with the endless belt 280. The endless belt 280 is mounted over idler rollers 284, 288, 290, 293, 295 mounted on shafts 283, 287, 289, 291, 297 extending across and journalled in the side members of the frame 10. A drive roller 292 secured to a shaft 266, which extends across the frame 10 and is journalled therein at each side, supplies the drive to the belt 280. A pulley 264 is secured to an outer end of the shaft 266 and a belt 262 extends between the pulley 264 and a pulley 260 mounted on the outer end of the shaft 246. With this arrangement the drive applied to the shaft 246 from the motor 60 also drives the endless belt 280. The endless conveyor 42 is mounted over the idler rollers 300, 302, secured to shafts

301, 303, journalled in the frame 10, and also over the idler rollers 290, 293, supporting the belt 280. The individual cords of the conveyor 42 are maintained in the desired spaced apart relationship by a plurality of adjustably spaced apart guide wheels 309. Each of the wheels 309 is mounted on an adjustable bearing arm 310 and the bearing arms 310 are mounted on a common shaft 312 extending transversely across the frame 10. The bearing arms 310 are slidably mounted on the shaft 312 and are each maintained by means of locking set screws 314.

The idler roller 295 mounted on the shaft 297 is positioned directly beneath and in substantial alignment with the guide wheels 309. The guide wheels 309 are set so as to be slightly above the roller 295 so that the cords of the conveyor 42 meet the surface of the belt 280 at this point to provide a paper engaging nip.

In order to feed the paper from the carriage 22 into the nip between the belts 42, 280, there is provided a plurality, in this case four (4), of spaced apart feed rollers 350 each of which is individually mounted on resiliently biased supporting shafts 352. Each of the shafts 352 include an outstanding flange 356 and each shaft is slidably engaged in an open ended cylinder 354 so that the flange 356 engages with and is adapted to compress a coil spring 358 housed within the cylinder 354. A locking nut 360 is threadably engaged with the end of the shaft 352 protruding beyond the cylinder 354 so as to retain the shaft in position and provide a means of adjusting the tension on the springs 358.

The centre pair 350a of the rollers 350 are also each provided with a drive pulley 351 and cord belts 353 are provided between the pulley 351 and a corresponding pair of drive pulleys 355 mounted on a spaced apart pair 309a of the guide wheels 309. See Figure 11 of the drawings. With this arrangement, as the guide wheels 309a are rotated by the cords of the conveyor 42 the feed rolls 350a are driven so as to act against the sheets of paper supported on the carriage 22 and impel the leading edge of the paper sheet into the nip between the conveyor belts 42 and 280.

The travel of the conveyor cords 42 is over the outside of the idler roller 293 exteriorly of the conveyor belt 280, over the idler roller 290, between the roller 290 and the belt 280, and then over the idler rollers 300, 302 to return over the guide wheels 309 between the wheels 309 and the idler roller 295. The paper when discharged from the carriage 22 is thus retained between the cords of the conveyor 42 and the belt 280 during its travel around the rollers 293, 290, until the paper reaches the idler roller 288, where the cord conveyor 42 ceases to contact the belt 280, and the paper is then ejected into the stacker 44. A heating element 320 is attached to the frame beneath the travel of the belts 280, and 42 so as to provide supplementary heat to aid in the drying of the ink on the ruled paper as it is carried along by the belt 280.

Rotary drying and cleaning brushes 700, 702 are mounted above the travel of the template supporting carriage 20 on standards 704, 706 so as to extend across the upper portion of the frame. The brush 700 is driven by a cord belt 708 from the idler roller 284 while the brush 702 is driven by a cord belt 710 from the idler roller 295. The brushes 700, 702 are positioned so as to frictionally contact the surface of the template 180 so as to dry and/or remove any surplus ink at the beginning and end of each ruling stroke.

Pen beams

The pen beams 24, 26 are of similar and known construction wherein the beam and pen clamp is in one complete unit which is mounted at each end to the standards 30, 32 so as to be adapted for pivotal movement relative to the frame 10. Beam end supporting frames 402 are journalled in the standards 30, 32 by means of shafts 404. Cam arms 406 are secured to the shafts 404 at one side of the frame and are adapted to be engaged by cam blocks 408, 410 mounted in spaced apart relationship on the control bar 81. Similar cam arms 407 are mounted on the shafts 404 on the other side of the frame so as to be in a position for engagement by the cam plates 412 mounted in the stepped slots 190 of the template supporting frame 160. The cam plates 412 preferably consist of straight metal strips of assorted lengths which are inserted in the slots 190, one for each pen beam in use, for the purpose of holding up the beams over a blank space on the paper, say an extra deep head, or when two or more forms are set on the paper, or at the end of the ruled lines. These cam strips are positioned so as to allow the pens to drop in as short a space as possible in the template or templates, or to raise the pens off the paper at the foot.

It is not necessary, nor is it intended that the cam strips 412 need be set exactly as is necessary with the controlling cams in prior art ruling machines as the template determines the exactness of the beginning or ending of ruled lines. It is contemplated, however, that if for any reason the present apparatus should be used without a template the cams 412 could be set exactly so as to function in the usual manner as is well known in the art. An extension bar 169 is provided on the template supporting carriage in front of and in alignment with the slots 190 for the purpose of contacting the cam arms 407 keeping the pen beams in raised position prior to the cams 412 coming into operation on the forward stroke.

The pen beams 24, 26 each include tapered openings 415 at each end and when the ends of the beams 24, 26 are placed within the channels 403 of the end supporting frames 404, tapered pins 420 are inserted in the openings 415 to hold the beams in place.

50 This arrangement permits easy interchangeability of the pen supporting beams and allows the pens to be set-up exteriorly of the machine if so desired. See Figure 13.

The pen beams 24, 26 are each adapted to clamp and retain a plurality of ruling pens 500 in the usual manner. The ruling pens 500 are of the usual construction and ink is supplied to each pen by means of an automatic ink fountain arrangement 502 mounted on the side of the frame 10 with tubes feeding to ink reservoirs mounted directly on the beams 24, 26.

In the set up illustrated each pen beam 24, 26 is ready for the ruling of lines in three different colours, let us say black, red and blue. Each of the beams 24, 26 is provided with a plate 520 extending beneath the rear edge of the beam and supporting a nested arrangement of ink pans, 522, 524, 526, see Figures 14 and 15. Wicks 530 extend from each of these pans to the groove of each ruling pen with the various colours being separated by shielding layers of suitable material 532, for example, layers of tinfoil.

Assuming that the reservoir 550 contains black ink, this reservoir is mounted in a main ink

supply pan 552 and ink is delivered from the pan 552 to the pans 522 on the beams 24, 26 by means of tubes 556 at each end of the pan 552. The tubes 556 are connected to the pan 552 so as to be capable of being pivotally swung towards and away from the pen beam ink pans so that the ink supply source can be selectively put into operation when and where desired. A similar reservoir 560 contains the red ink which is supplied from an ink pan 562 through tubes 564, to the pans 524 on the beams 24, 26. The blue ink is supplied from a reservoir 570 and ink pan 572 in a similar manner, and tubes 576 to the ink pans 526. Each of the reservoirs 550, 560 and 570 are constructed and mounted in the manner shown in Figure 16. The reservoir bottle proper say 550, is threadably engaged with a fitting 600 mounted above the bottom of each ink supply pan and a float valve 602 in the fitting 600 controls the level of the ink wherein reservoir bottles are immersed.

This arrangement provides for the quick and easy changing of ink colours or replenishment of ink sources without the necessity of changing or adjustment of the pen beams and pen set-up.

All the pens used in the present arrangement may be "cut" so as to eliminate the possibility of "full" or blind lines in close ruling. This presents a distinct advantage over the prior art machines as "cut" pens could only be used in cross lining and not in down lining due to the setting-up. All lines of any one colour may be set-up in one beam regardless of where the line starts and ends.

It is also contemplated that the present machine could be used with other ruling elements mounted on the interchangeable beams. For example, grooved ruling discs mounted in spaced apart relationship for rotation on shafts supported by a beam arrangement similar to that shown and described might be employed instead of pens. The only modifications necessary would be the substitution of inking rollers in place of the present fountains and wicks.

I claim:

1. A ruling machine having in combination with a supporting frame, a ruling element supporting beam pivotally mounted above said frame so as to extend transversely across said frame, a template carrying frame mounted on said supporting frame for horizontal reciprocal movement beneath said element supporting beam, a thin flat template mounted on said template carrying frame, a paper supporting carriage mounted on said frame for horizontal reciprocal movement beneath said template carrying frame, means connecting said template carrying frame to said paper supporting carriage, means to reciprocate said paper supporting carriage, paper feeding means adapted to feed single sheets of paper on to said paper supporting carriage, and means on said template carrying frame and supporting frame adapted to pivot said ruling element supporting beam towards and away from operative contact with said template during the reciprocal movement of said template carrying frame.

2. A ruling machine as claimed in claim 1, wherein said template carrying frame is mounted for sliding movement on a guiding track fixedly attached to the upper portion of said supporting frame, said paper supporting carriage is mounted for sliding movement on a guiding track mounted for restricted vertical movement on said

frame beneath said template supporting frame, guiding track and there are means for actuating said paper supporting carriage guiding track vertically towards and away from said template supporting frame guiding track.

3. A ruling machine as claimed in claim 1, wherein said paper supporting carriage comprises of a plurality of hingedly connected segments adapted to flex into and out of horizontal alignment during the travel of said carriage along said guiding track.

4. A ruling machine as claimed in claim 1, wherein there are a plurality of ruling element supporting beams, pivotally mounted on said frame in spaced apart relationship.

5. A ruling machine as claimed in claim 1, wherein the means on said template supporting frame and main supporting frame adapted to pivot said ruling element supporting beam comprises outwardly extending cams mounted on said template carrying frame and supporting frame and lever arms projecting from the ends of said beam in the path of said cams.

6. A ruling machine having in combination with a supporting frame, a ruling element supporting beam pivotally mounted on said frame so as to extend transversely across the upper portion of said frame, a template carrying frame mounted for sliding movement on said frame beneath said element supporting beam, a thin flat template mounted on said template carrying frame, a paper supporting carriage mounted for sliding reciprocal movement on said frame beneath said template carrying frame, connecting means between said paper supporting carriage and template carrying frame adapted to move said template carrying frame during reciprocal movement of said paper supporting carriage, feeding means mounted on said frame adapted to selectively feed a single sheet of paper to said paper supporting carriage at the beginning of said reciprocal movement, means to reciprocate said paper supporting carriage, paper ejecting means mounted on said frame adapted to remove a sheet of paper from said paper supporting carriage at the end of said reciprocal movement, and means on said template carrying frame and main supporting frame adapted to pivot said ruling element supporting beam towards and away from operative contact with said template during the reciprocal movement of said paper supporting carriage and template carrying frame.

7. A ruling machine as claimed in claim 6, wherein there are a plurality of ruling element supporting beams pivotally mounted on said frame in spaced apart relationship.

8. A ruling machine as claimed in claim 6, wherein the means on said template carrying frame and main supporting frame adapted to pivot said ruling element supporting beam comprises outwardly extending cams mounted on said template carrying frame and supporting frame and lever arms projecting from the ends of said beam in the path of said cams.

9. A ruling machine as claimed in claim 6, wherein said paper supporting carriage comprises of a plurality of hingedly connected segments adapted to flex into and out of horizontal alignment during the travel of said carriage along said guiding track.
